(57) **CLAIM**

The ornamental design for a driver for an internally driven dental implant, as shown and described.

DESCRIPTION

This application is related to Ser. No. 29/216,156, for an internally driven dental implant, of common ownership with the present application, filed Nov. 1, 2004.

FIG. 1 is a top perspective view of an internally driven dental implant showing our new design;

FIG. 2 is a bottom perspective view thereof;

FIG. 3 is a side elevational view thereof; and,

FIG. 4 is a bottom plan view thereof.

The broken line showing of environment in the figure drawings is for illustrative purposes only and forms no part of the claimed design.
